SALVAGING GRAPPLER

Claude Byler, Buffalo, Wyo.

Application January 10, 1933, Serial No. 651,040

8 Claims. (Cl. 114—55)

This invention relates to improvements in grapples or tongs, and more particularly to a novel tong construction designed to lift extremely heavy loads such as sunken ships and the like.

5 In my application Serial No. 639,073, filed October 22, 1932, I have disclosed an improved apparatus for salvaging submerged ships or treasure, and such apparatus includes a grapple of sufficient size to form a cradle about a relatively 10 large sunken ship, so that such a ship may be elevated above the water surface where treasure may be removed from the same. As the grapple must be of gigantic size, it is apparent in actual practice, ordinary tongs cannot be used. One 15 of the objects of the invention is to incorporate in such a grapple, tong arms which are not only light in comparison with their size, but which are reinforced to automatically and yieldingly take care of strains on the tong arms, particularly at their tips.

20 Another object is to furnish tong arm reinforcements of yielding construction to conform to the shapes of the sides of ships to prevent crushing of the hull of a vessel while the latter is being salvaged.

25 A still further object is to supply a grapple in which each tong arm is provided with a nozzle for discharging a jet of pressure fluid from the tip of each tong arm; the nozzles of the various 30 tong arms being connected to a suitable header arranged alongside of the grapple and furnished with pressure fluid by a flexible hose which may be wound about a weight on the pontoon ship from which the grapple is operated.

35 With the foregoing objects outlined and with other objects in view which will appear as the description proceeds, the invention consists in the novel features hereinafter described in detail, illustrated in the accompanying drawings, and 40 more particularly pointed out in the appended claims.

In the drawings,

Fig. 1 is a side elevation of a portion of the improved grapple with parts removed to facilitate 45 illustration.

Fig. 2 is a transverse vertical sectional view of the same, taken on the line 2—2 of Fig. 1.

Referring to the drawings, 3 designates a main 50 shaft or axle extending the full length of the grapple. Pairs of crossed tong arms 4 are pivotally mounted on the shaft and consist of lower portions 5 and upper portions 6. The ends of the upper portions are pivotally connected at 7 to links 8 which in turn are pivotally connected 55 at 9 to a tackle block 10 that is raised and

lowered by a cable 11 which is wound on a winch, not shown, on the pontoon ship that supports the grapple. From Fig. 1 it may be seen that there is a separate grapple for each tackle block 10, in order that the power of a large 60 number of winches may be applied during the lifting of the load.

To decrease weight and to add strength at points where needed, each tong arm is preferably of fabricated construction, and the tongs of each 65 pair may be opened and be held in open position by any suitable means. For example, the lower portion of each arm may have medially of its length, an eye 12 connected to a tackle block 13 suspended from a cable 14 which is wound about 70 a suitable winch, not shown, on the pontoon ship. By properly operating the winches connected to the cables 14, it is obvious that the tong arms may be held in the dotted line position shown in Fig. 2, while the grapple is descending, in order 75 that it may be brought to rest on the top of a sunken vessel, and after the tongs have been closed by raising the tackle blocks 10, the cables 14 can be used to assist in elevating the load. Owing to the massiveness of the tongs, it is practically necessary that they be internally reinforced. I accomplish this in a manner to permit 80 the tongs to flex slightly and to also grasp the hull of a ship without crushing the latter. For example, each tong arm may have a reinforcement 85 consisting of a flexible cable 15 having its lower end secured to the arm adjacent its tip, as shown at 16. The upper end of the cable terminates in a rod terminal 17 which is slidable 90 through a hole 18 that extends through the medial portion of the lower part of the tong arm. A member 19 loosely fits on the rod terminal 17 and bears against the outer surface of the arm, and a coil spring 20 surrounds the part 17 and bears at 95 its lower end against the member 19, and at its upper end, against a washer 21, which may be adjusted along the part 17 by a nut 22 which engages threads on the part 17.

It will be appreciated from the above that 100 bending strains tending to straighten out any one of the tong arms, will be yieldingly resisted by such reinforcement, and furthermore, as the cables 15 are flexible, a ship cradled within the grapple will not be crushed, as would be the 105 case if the parts 15 were rigid.

As it is essential that the tong arms on each 110 side of the grapple simultaneously open or close, the medial portions of the lower parts 5 of the arms are rigidly connected together by reinforce-

ing rods 23, which, like the shaft 3, preferably extend the full length of the grapple.

As many sunken vessels sink into sand or the like at the bottom of the sea, it is necessary that such sand or other material be loosened from about the ship to assist the tong arms in taking hold. I have therefore provided each tong arm with a pressure fluid nozzle 24. These nozzles have their outlet ends 25 positioned at the tips of the arms, and their inlet ends are connected to headers 26 which extend along the sides of the grapple. The headers are fed with a pressure fluid such as compressed air from one or more flexible hose 27 which may be wound on winches, not shown, on the pontoon ship.

From the foregoing it is believed that the construction, operation and advantages of the invention may be readily understood by those skilled in the art, and it is obvious that changes may be made in the details disclosed, without departing from the spirit of the invention, as expressed in the claims.

What is claimed and desired to be secured by Letters Patent is:

26. 1. A grapple comprising pivotally connected tong arms, each arm having a substantially semi-circular portion terminating in a tip, and a flexible reinforcing member extending across the curved portion of each arm and having one of its ends secured to the arm adjacent its tip, and its other end portion connected to the arm at a point spaced from the tip, said reinforcing member consisting of a flexible cable provided at one end with a coiled spring functioning to keep the cable taut.
36. 2. A grapple comprising pivotally connected tong arms, each arm having a substantially semi-circular portion extending from its pivot point to its tip, a flexible cable having one of its ends secured to the tip portion of the arm, the other end portion of the cable being provided with a rod terminal extending through the arm at a point adjacent its pivot point, and yielding means for holding the cable taut.
45. 3. A grapple comprising pivotally connected tong arms, each arm having a substantially semi-circular portion extending from its pivot point to its tip, a flexible cable having one of its ends secured to the tip portion of the arm, the other end portion of the cable being provided with a rod terminal extending through the arm at a point adjacent its pivot point, and yielding means for holding the cable taut, the last mentioned means including abutments on said rod terminal and a coil spring positioned between said abutments.
55. 4. A grapple comprising a main shaft, a series of pairs of crossed rigid tong arms pivotally mounted on said shaft, the arms of each pair having upper portions positioned above the shaft and substantially semi-circular lower portions positioned below the shaft and terminating in tips extending toward one another, means for moving the ends of the upper portions of the arms toward and away from one another, and flexible reinforcements for the lower portions of the arms,

extending from the tips of the latter tangentially across the semi-circular portions of the arms and through the latter at points spaced from opposite sides of said shaft, said reinforcements being spaced apart throughout their lengths.

5. A grapple comprising a main shaft, a series of pairs of crossed tong arms pivotally mounted on said shaft, the arms of each pair having upper portions positioned above the shaft and substantially semi-circular lower portions positioned below the shaft, means for moving the ends of the upper portions of the arms toward and away from one another, flexible reinforcements for the lower portions of the arms, extending from the tips of the latter tangentially across the semi-circular portions of the arms and through the latter at points adjacent to said shaft, and yielding means for maintaining said flexible reinforcements in taut condition.

6. A grapple comprising a main shaft, a series of pairs of crossed rigid tong arms pivotally mounted on said shaft, the arms of each pair having upper portions positioned above the shaft, and substantially semi-circular portions positioned below the shaft, said lower portions terminating in tips and the tips of each extending toward the tip of the other, means for moving the ends of the upper portions of the arms toward and away from one another, yielding reinforcements for the lower portions of the arms, each of said reinforcements extending from the tip of the lower portion of the arms tangentially across the semi-circular portion, and through the latter at a point spaced from said shaft, said reinforcements being spaced apart throughout their lengths and converging toward said tips, and resilient means cooperating with the arms and reinforcements for holding said reinforcements taut.

7. A grapple comprising rigid tong arms having substantially curved portions terminating in tips, flexible reinforcements extending across the curved portions and connecting spaced points on said arms, said reinforcements being spaced apart throughout their lengths to accommodate an object between them, and yielding means cooperating with said reinforcements to normally hold them in taut condition.

8. A grapple comprising crossed rigid tong arms, means pivotally connecting said arms, the arms having upper portions above the last mentioned means, the arms having substantially semi-circular lower portions positioned below said means and terminating in tips extending toward one another, means for moving the ends of the upper portions of the arms toward and away from one another, and flexible reinforcements for the lower portions of the arms, extending from the tips of the latter tangentially across the semi-circular portions of the arms to points spaced from opposite sides of said means, said reinforcements being spaced apart throughout their lengths, and yielding means for maintaining said flexible reinforcements in taut condition.

CLAUDE BYLER.
